(57) **CLAIM**

We claim the ornamental design for a cartridge for a fluid delivery apparatus, as shown and described.

DESCRIPTION

FIG. 1 is a perspective view of a cartridge for a fluid delivery apparatus of our new design.

FIG. 2 is a front elevation view thereof.

FIG. 3 is a back elevation view thereof.

FIG. 4 is a right side view thereof.

FIG. 5 is a left side view thereof.

FIG. 6 is a top plan view thereof; and,

FIG. 7 is a bottom plan view thereof.

The dashed broken lines depict portions of the cartridge for a fluid delivery apparatus that form no part of the claim. The dash-dot-dash broken lines show the boundary of the claimed design and form no part of the claim.
